UNITED STATES PATENT OFFICE.

SILAS E. BAILOR, OF TARKIO, MISSOURI.

CULTIVATOR.

No. 876,513.

Specification of Letters Patent.

Patented Jan. 14, 1908.

Application filed January 31, 1907. Serial No. 365,140.

To all whom it may concern:

Be it known that I, SILAS E. BAILOR, a citizen of the United States, residing at Tarkio, in the county of Atchison and State 5 of Missouri, have invented a new and useful Cultivator, of which the following is a specification.

The invention relates to improvements in cultivators.

10 The object of the present invention is to improve the construction of cultivators, more especially the means for controlling the gangs of cultivating devices for enabling the same to be raised and lowered to arrange the 15 plows for operating at the desired depth.

A further object of the invention is to provide an adjusting device capable of enabling the members of each gang of plows to be raised and lowered both simultaneously and 20 independently with a single operating lever and of automatically locking one of the members in its adjustment, when the adjusting means is set for raising and lowering the other member.

25 Another object of the invention is to provide simple and efficient means for adjusting the gangs of plows toward and from each other, and for swinging the same laterally simultaneously with the carrying wheels for 30 turning the machine.

Also the invention has for its object to enable the gangs of plows and the carrying wheels to be shifted laterally either by hand, or foot in guiding the machine.

35 With these and other objects in view, the invention consists in the construction and novel combination of parts hereinafter fully described, illustrated in the accompanying drawings, and pointed out in the claims 40 hereto appended; it being understood that various changes in the form, proportion, size and minor details of construction, within the scope of the claims, may be resorted to without departing from the spirit or sacrificing 45 any of the advantages of the invention.

In the drawings:—Figure 1 is a plan view of a cultivator, constructed in accordance with this invention. Fig. 2 is a rear elevation of the same partly broken away at the 50 center to illustrate the construction for shifting the gangs of plows and the carrying wheels laterally. Fig. 3 is a longitudinal sectional view, taken substantially on the line 3—3 of Fig. 1. Fig. 4 is an enlarged detail

perspective view, illustrating the manner of 55 mounting the adjustable plow beams. Figs. 5, 6 and 7 are enlarged transverse sectional views, illustrating the construction of the adjusting device for raising and lowering the plow beams and showing the several positions of the adjusting device. Fig. 8 is an 60 enlarged sectional view, taken longitudinally of the adjusting device for raising and lowering the plow beams. Fig. 9 is a detail perspective view of the shiftable engaging dog or 65 detent. Fig. 10 is a detail perspective view of the shiftable locking device for holding one of the plow beams during the adjustment of the other plow beam. Fig. 11 is a detail 70 sectional view of the pinion and the inclined operating shaft. Fig. 12 is a sectional view on the line y—y of Fig. 11. Fig. 13 is a detail view of the central crankshaft for actuating the shiftable transverse bar or member. Fig. 14 is a detail view, illustrating the construction of the rack bars and pinion for 75 moving the gangs of plows toward and from each other. Fig. 15 is an enlarged detail view, illustrating the manner of connecting the ends of the arches with the oscillatory 80 hangers. Fig. 16 is an enlarged detail sectional view, illustrating the construction for locking the inclined operating shaft against rotary movement.

Like numerals of reference designate corresponding parts in all the figures of the drawings.

1 designates an axletree, preferably consisting of two metal bars or members spaced apart at their ends by shanks 2 of bearing 90 brackets 3, having bearings for the reception of vertical pivots 4 of crank axles 5, upon which are mounted carrying wheels 6. The vertical pivots of the crank axles are secured in the bearings of the brackets 3 by means of 95 keys, or other suitable fastening devices, and the crank axles are provided with forwardly extending arms 7, which are connected at their front ends by pivots 8 to the terminals of a transversely disposed shiftable 100 bar 9, adapted to be moved transversely of the machine, by the means hereinafter described, for changing the position of the carrying wheels with relation to the frame of the machine, to enable the latter to be 105 properly guided.

The machine is provided with a pair of draft beams 10, which are secured at their

rear ends to the axletree and which support a transverse frame bar 11, constructed of angle iron, or other suitable material and secured to the lower face of the draft beams 5 or tongues 10.

The plow beams 12, which may be constructed in any preferred manner and which may be equipped with front and rear plows 13 and 14, or other suitable cultivating devices, are mounted at their front ends on laterally extending pivots 15 of transversely disposed arches 16. The plow beams are provided at their front ends with suitable eyes 17 for the reception of the pivots 15, 15 and they are secured on the same by keys 18, or other suitable fastening devices. Any other suitable means may, however, be employed for hingedly mounting the front ends of the plow beams on the arches, which constitute connecting means for properly spacing the members of each gang of plows.

The connecting arches, which are shiftable laterally of the machine to arrange the gangs of plows the desired distance apart, are provided at the lower ends of their sides adjacent to the inner ends of the pivots 15 with eyes 19, through which pass front vertical sides or pivots 20 of hangers 21, which are also provided with rear vertical pivots or 30 sides 22. The front and rear sides or pivots 20 and 22 are connected by an inclined integral bottom portion, each hanger 21 being preferably constructed of a single piece of rod metal, or other suitable material. The 35 hangers 21 are mounted at their rear sides or ends in bearing brackets 23, arranged vertically and secured to the front bar or member of the axletree, and provided at the top and bottom with vertically aligned bearings 40 24, consisting of forwardly projecting perforated lugs or ears, through which pass the rear pivots 22 of the hangers. The hangers are arranged in pairs, the members of each pair being parallel, and they are adapted to 45 swing laterally of the machine to carry the connecting arches and the gangs of plow beams thereof toward and from each other, and the members of each pair of hangers maintain their parallel relation in all the 50 adjustments of the gangs of plows. Each hanger is braced by an inclined rod 25, extending downwardly and forwardly from the upper end of the rear pivot 22 of the hanger to the lower end of the front vertical 55 pivot 20 of the same. The upper ends of the rear pivots are provided with adjustable collars 26, or other suitable means for retaining the hangers in the bearings of the brackets 23. Each pair of hangers is further 60 braced by inclined converging bracing rods 27, united at their front ends to form a substantially V-shaped brace, and provided at their lower ends with eyes 28, which are arranged on the rear pivots 22 at the lower 65 ends thereof. The V-shaped braces extend

forwardly and upwardly from the lower ends of the rear pivots to the frame bar 11, and are bolted, or otherwise secured to the same. The eyes 28 at the lower ends of the sides of the V-shaped braces are interposed between 70 the lower ears of the bearing brackets and the bottom connecting portions of the hangers.

The inner and outer plow beams of each gang of plows are connected by links or rods 75 29 with arms 30 and 31, which extend forwardly from a transversely disposed rock shaft 32. The links or rods 29 pass through perforations of L-shaped brackets or plates 33 of the plow beams, and they have upper 80 and lower spiral springs 34 and 35 disposed on them for yieldably connecting the plow with the arms 30 and 31. The lower springs yieldably support the plow, and thereby cushion the connections in raising the plows, 85 and the upper springs operate to yieldably hold the plows in the ground.

Each rock shaft is journaled in suitable bearings and is supported by inner and outer laterally movable bars or members 36 and 90 37, extending longitudinally of the machine and provided at their front ends with vertical bearing eyes 38, which are secured on the upper ends of the front pivots 20 by means of upper and lower collars 39. The upper 95 and lower collars are provided with set screws 40, and adjustably support and retain the bearing bars or members 37 on the front pivots of the hangers. The bearing bars 36 and 37, which are connected at their 100 rear ends by the rock shaft 32 and which are pivoted at their front ends to the hangers 21, are maintained in parallelism and are adapted to be shifted or moved transversely of the machine in adjusting the gangs of plows to- 105 ward and from each other.

The inner and outer arms are loose and fast, respectively, with relation to the rock shaft 32, the outer arm 31 being fixed to the shaft by means of a set screw 41. The inner 110 arm 30 is provided at its inner or rear end with an eye or sleeve 42 to receive the rock shaft 32, and it is provided with an upwardly and rearwardly extending sector-shaped plate or member 43, preferably cast integral 115 with the arm 30, but it may be rigidly connected with the said arm 30 in any other preferred manner. The shaft 32 also carries a similar sector-shaped plate or member 44, and these two plates or members 43 and 44, which are spaced apart and which correspond with the arms 30 and 31, are loose and fast, respectively, with relation to the shaft 32, the sector-shaped plate or member 44 being fixed to the shaft by means of a set screw 45, or other suitable fastening means. Each of 120 these sector-shaped plates or members is provided with inner and outer arcuate series of ratchet openings 46 and 47, adapted to be engaged by the means hereinafter described, 130

for locking the said sector-shaped plates or members against movement to retain the plows at any adjustment, and for also connecting either or both of the sector-shaped 5 plates or members with an operating lever for raising and lowering the plow.

Either of the sector-shaped plates or members may be locked at any adjustment by means of a shiftable locking device 48, slide- 10 able on the shaft 32 and slidably connected with the inner bearing bar, which is pro- 15 vided with a guide or loop 49 for holding the shiftable locking device against rotary move- 20 ment. The shiftable locking device is com- 25 posed of two sides 50 and a connecting loop 51, consisting of two side portions and a transverse connecting portion, which pass 30 through the guide 49 of the inner bearing bar 36. The sides 50 of the shiftable locking de- 35 vice 48 are provided at their lower ends with bearing openings or eyes 52, through which the shaft 32 passes, and the said sides are provided at their upper ends with inwardly 40 extending lugs or projections 53, preferably 45 arranged in sets of three, but one or more may be employed, as will be readily under- 50 stood. When the locking device 48 is in a central position, as illustrated in Fig. 5 of the 55 accompanying drawings, the lugs or projec- 60 tions 53 of the said device 48 are located be- 65 yond and are out of engagement with the sector-shaped plates or members 43 and 44. Any lateral movement of the locking device 70 from this position will carry one set of lugs or 75 projections into engagement with one of the sector-shaped plates or members, and will move the other set of lugs or projections out- 80 wardly from the other plate or member, as clearly illustrated in Figs. 6 and 7 of the 85 accompanying drawings. This movement of the shiftable locking device 48 is effected through a slid- 90 able detent 54, which releases the sector-shaped plate or member, that is engaged by the locking device. The detent 95 54, which is in the form of a rectangular block or piece, is provided at its ends with 100 projecting fingers or lugs 55, located at opposite sides of the adjusting device and prefer- 105 ably arranged in sets of three to correspond 110 with the lugs or projections 53 of the shift- 115 able locking device. When the detent 54 is in a central position, as illustrated in Fig. 5 120 of the accompanying drawings, the fingers 55 are in engagement with each of the sector- 125 shaped plates or members, and their outer 130 terminals bear against the locking device, and positively maintain the same out of engagement with the sector-shaped plates or members. The sides of the locking device 135 are provided with arcuate braces 56, presenting arcuate faces to the ends of the fingers 55 of the detent 54 and enabling the said fingers to slide freely on the side portions of the locking device. When the detent 54 is in the 140 central position, illustrated in Fig. 5 of the

drawings, the fingers 55 extend through both of the arcuate plates or members and their outer ends engage the side portions of the locking device and maintain the lugs or projections thereof positively out of engagement 70 with the sector-shaped plates or members, and when the detent is moved from the central position, shown in Fig. 5, to either of the side positions, illustrated in Figs. 6 and 7, it does not release either of the sector-shaped 75 plates or members, until such plate or member is engaged by one of the sides of the shiftable locking device, so that when it is desired to adjust one of the plows of either gang, there is no liability of affecting the ad- 80 justment of the other plow of such gang. The braces 56 of the sides of the shiftable locking device 48 are connected at their lower ends with the sides 50 of the locking device by short bottom portions, as clearly illustrated 85 in Fig. 10 of the drawings.

The detent 54 is slidable in spaced guides 57 of an operating lever 58, which has a forked or bifurcated lower portion for strad- 90 dling a centrally arranged toothed ratchet member 59 of sector-form, as clearly illus- 95 trated in Fig. 8 of the drawings. The lower ends of the sides of the forked portion of the operating lever are provided with suitable bearing openings for the shaft 32, and the 100 upper ends 60 of the said sides are bolted, or otherwise secured to the lever, but they may be formed integral with the same, as will be readily understood. The toothed ratchet plate or member 59 is provided with 105 a bearing eye or sleeve 61 for the reception of the shaft 32, and it has a depending lug or flange 62, to which the rear end of the inner bearing bar 36 is bolted, or otherwise secured, whereby the central ratchet plate 110 or member 59 is held against rotary move- 115 ment and a support provided for the adjacent end of the shaft 32. The guides 57 are provided with oblong openings to re- 120 ceive the end portions of the detent 54, which is provided with a central slot 63 for a crank arm 64 of a shaft 65. The shaft 65, which is journaled in upper and lower bearings 66 of 125 the lever 58, is provided at its upper end with a substantially U-shaped portion, the upper side 67 of which constitutes a grip or handle. The grip or handle 67 of the crank shaft 65 constitutes the handle of the operating lever, and it is adapted to be grasped by the operator for enabling the operating 130 lever 58 to be swung backwardly or forwardly, and it is also capable of a lateral os- 135 cillatory movement to rock the shaft 65 for moving the detent 54 to any of its several positions. The operating lever 58 is locked 140 at any adjustment by means of a spring- 145 actuated pawl or dog 68, suitably mounted on the lever and arranged to engage the central ratchet member 59, as clearly illustrated 150 in Fig. 8 of the drawings. The pawl or dog 155

is connected by a wire 69, or other suitable means, with a latch lever 70, pivotally mounted on the crank shaft 65 at the handle portion thereof and provided with an arm, 5 forming a grip or handle and arranged to be grasped simultaneously with the grip or handle by the crank shaft 65. The latter lever 70 is of bell crank form and its other arm is connected with the wire 69. By this 10 construction, the operating lever may be readily released or locked and may be instantly connected with either or both of the sector-shaped plates or members 43 and 44, and when it is moved into engagement with 15 only one of such plates or members 43 and 44, the other plate or member is automatically locked and retained in its adjusting position.

The inner bearing bars 36 are connected 20 with upper and lower transversely disposed rack bars 71 and 72, provided at their outer ends with upwardly extending arms 73 and 74, having openings 75 for the reception of the bearing bars 36. The upper rack bar 25 71 is provided at its lower edge with teeth, which meshes with a pinion 76, and the latter also meshes with the teeth of the lower rack bar 72, which has its teeth at its upper edge, as clearly illustrated in Fig. 13 of the 30 drawings. The toothed portions of the rack bars, which are spaced apart and are arranged in parallelism with each other, extend through a substantially U-shaped guide 77, consisting of a pair of guiding arms 78 35 and a bottom connecting portion. The guiding arms 78 are provided with openings through which the rack bars pass, and the guide 77 is thereby supported by the rack bars.

40 The pinion 76, which is provided with hub extensions 79, is journaled in bearing openings of a pair of plates 80, secured to the bottom connecting portion of the guide 77 at the center thereof and extending upwardly therefrom, as clearly illustrated in 45 Figs. 11 and 13 of the drawings. When the pinion is rotated, the rack bars will be actuated and their upwardly extending arms 73 and 74 will be moved toward and from each 50 other to adjust the gangs of plows laterally of the machine. When the rack bars are adjusted, the hangers will be swung laterally, and the means for raising and lowering the plows will be carried by the hangers in 55 their adjustment, as will be readily understood.

The pinion 79 is provided with an oppositely flared opening 81, having grooves 82 for the reception of tapering ribs or keys 83 60 of an inclined operating shaft 84, which extends through the pinion, and which is capable of both rotary and lateral movement to adjust the gangs of plow beams. The inclined operating shaft is provided near its lower end with a substantially semi-spherical

head 85, which is arranged in a socket 86 of a bracket 87, and the latter depends from the transverse frame bar 11 at the center thereof. The semi-spherical head 85 of the inclined operating shaft is provided with suitable projections or teeth 88, which are adapted to engage corresponding grooves or recesses 89 of the bottom of the socket 36, whereby the head of the inclined operating shaft is operated with the socket and is held 75 against rotary movement. The inclined operating shaft is retained in its interlocked relation with the socket by means of a coiled spring 90, disposed on the lower portion of the shaft and interposed between the socket 80 86 and a nut 91, but any other suitable means may be provided for locking the shaft against rotary movement. The spring yieldably holds the head 85 of the inclined shaft in engagement with the socket 86, and it permits 85 the head to be drawn from engagement with the socket by a longitudinal movement of the inclined shaft for rotating the latter. The inclined operating shaft is provided at its upper or rear end with a suitable grip or 90 handle 92, and it is adapted to be partially rotated to operate the rack bars, and it is also capable of being oscillated to shift the transverse bar 9 and the gangs of plows, as hereinafter explained. The opening 93 of 95 the bottom socket 86 is sufficiently large to permit the inclined shaft to be oscillated for moving the carrying wheels and the gangs of plows laterally in changing the direction of the machine.

100 The oppositely tapered ribs or keys 83 and the flaring of the opening of the pinion facilitate the oscillatory movement of the inclined operating shaft, and the latter passes through a vertical guide 94 of the shiftable bar 9 for connecting the latter to the shaft. The guide 94 is in the form of a loop, which permits the inclined operating shaft to be raised and lowered to disengage it from and to engage it with a ratchet 95. The ratchet 95, 110 which is adapted to hold the inclined operating shaft against lateral movement, consists of a plate or member centrally secured between the bars or members of the axletree and extending upwardly and downwardly 115 therefrom, the upwardly extending portion being provided with a horizontal series of teeth, forming intervening spaces or recesses to receive the inclined operating shaft.

120 The inclined shaft, which operates in the nature of a lever, enables the gangs of plows and the carrying wheels to be shifted laterally by hand. In this adjustment of the parts, the plow beams and the means for raising and lowering the same maintain a 125 constant relative position through the hinge connection between the front sides of the hangers and the bearing bars and arches, which hinged connections permit the hangers to be arranged at different angles with rea- 130

tion to the plow beams and the bearing bars. This operation, however, may be effected by foot, and the guide loop 94 of the shiftable bar 9 receives a crank arm 97 of a centrally arranged longitudinally disposed crank shaft 98, journaled at an intermediate point in a suitable bearing 99 of a bracket 100, and supported at its rear end 101 by the depending portion of the ratchet plate or member 95.

10 The depending portion of the ratchet plate or member 95 is provided with a bearing opening for the crank shaft 98, which has its rear end reduced to form a journal and to provide a shoulder for engaging the lower portion of the ratchet plate or member.

15 The bracket 100, which is composed of two sides and a central connecting portion, is secured to and depends from horizontal seat supporting bars 102, which are supported at an intermediate point by the axle-tree. The front ends 103 of the seat supporting bars are secured to hanger plates or knees, which are bolted, or otherwise secured to the transverse frame bar 11, as clearly 20 illustrated in Fig. 4 of the drawings.

25 The crank shaft 98 is provided with laterally extending arms 104, which are connected by links 105 with treadles or foot levers 106, pivoted at their front ends to the lower terminals of the sides of the bracket 100 and provided at their rear ends with suitable plates for the accommodation of the feet of the driver. When either of the treadles or foot levers 106 is depressed, the rock shaft 30 35 98 will be partially rotated, and the crank arm 97 will shift the transversely disposed bar or member 9 in one direction or the other. This will change the direction of the carrying wheels, and as the gangs of plows 40 are connected with the shiftable bar or member 9 through the inclined operating shaft, they will be shifted simultaneously with the carrying wheels. In changing the direction of the machine, it is necessary to disengage 45 the rear portion of the inclined operating shaft from the ratchet member 95 to permit the said shaft to swing laterally.

Having thus fully described my invention, what I claim as new and desire to secure by 50 Letters Patent, is:

1. In a cultivator, the combination of a frame, oscillatory hangers pivotally mounted on the frame, cultivating devices arranged in gangs and carried by the hangers in an oscillatory movement thereof, and adjusting means for raising and lowering the cultivating devices, said adjusting means being also mounted on and carried by the hangers.

2. In a cultivator, the combination of a frame, oscillatory hangers mounted on the frame, cultivating devices hingedly connected with and carried by the hangers, and adjusting means for raising and lowering the cultivating devices, said adjusting means being also hingedly connected with the hangers.

3. In a cultivator, the combination of a frame, longitudinal hangers hinged at the back to the frame, arches carried by and connecting the front portions of the hangers, and cultivating devices connected to the 70

4. In a cultivator, the combination of a frame, oscillatory hangers hinged at the back to the frame, means hinged to the front portions of the hangers and connecting 75 the same, and cultivating devices carried by the hangers in their oscillatory movement.

5. In a cultivator, the combination of a frame, oscillatory hangers hinged at the back to the frame, means hinged to the front portions of the hangers and connecting the same, and cultivating devices pivotally connected with the hangers and carried by the same in their oscillatory movement, said cultivating devices being arranged to swing upwardly 80 85 and downwardly.

6. In a cultivator, the combination of a frame, oscillatory hangers hinged at the back to the frame, means for connecting the front portions of the hangers, cultivating devices carried by the hangers, supporting means mounted on the hangers at the front portions thereof, and an adjusting device carried by the supporting means and connected with the cultivating devices. 90 95

7. In a cultivator, the combination of a frame, oscillatory hangers mounted on the frame, cultivating devices carried by the hangers, supporting bars or members also carried by the hangers and hingedly connected with the same, and an adjusting device mounted on and carried by the supporting bars or members and connected with the cultivating devices. 100

8. In a cultivator, the combination of a frame, oscillatory hangers hinged at the back to the frame, an arch hinged to the hangers at the front thereof and connecting the same, said arch being provided with pivots, cultivating devices mounted on the pivots, supporting bars or members hinged to the hangers at the front thereof, and an adjusting device connecting the supporting bars or members and also connected with the cultivating devices for raising and lowering the same. 105 110

9. In a cultivator, the combination of a frame provided with bearing brackets, oscillatory hangers having front and rear vertical pivots, the rear pivot being mounted 120 in the bearing brackets, an arch connecting the hangers and provided with openings receiving the front pivots, cultivating devices mounted on the arches and carried by the hangers in the oscillatory movement 125 thereof, longitudinal supporting bars or members provided at their front ends with eyes arranged on the front pivots of the hangers, and an adjusting device connected with the cultivating devices for raising and 130

lowering the same, said adjusting device embodying a transverse shaft mounted on and connecting the rear ends of the supporting bars or members.

5 10. In a cultivator, the combination of a frame, longitudinal hangers having front and rear pivots, the rear pivots being connected with the frame, means for connecting the front pivots of the hangers, cultivating devices carried by the hangers, inclined braces extending from the upper ends of the rear pivots to the lower ends of the front pivots, and a substantially V-shaped brace extending from the lower ends of the rear 15 pivots to the main frame at a point between the front pivots.

11. In a cultivator, the combination of a frame, oscillatory hangers hinged at the back to the frame, cultivating devices carried by 20 the hangers, supporting means also carried by the hangers and located above the cultivating devices, and an adjusting device for raising and lowering the cultivating devices, said adjusting device comprising a trans- 25 verse shaft connecting the said supporting means, arms extending from the shaft and connected with the cultivating devices, and means for swinging and locking the arms.

12. In a cultivator, the combination with 30 cultivating devices, of a shaft having a fixed arm connected with one of the cultivating devices, a loose arm mounted on the shaft and connected with the other cultivating device, an operating lever mounted on the 35 shaft, means for connecting either or both of the arms with the lever, and means for automatically locking either of the arms when the other arm is connected with the lever.

13. In a cultivator, the combination with 40 cultivating devices, of a shaft having a fixed arm connected with one of the cultivating devices, a loose arm mounted on the shaft and connected with the other cultivating device, an operating lever mounted on the 45 shaft, means for connecting either or both of the arms with the lever, and means for automatically locking either of the arms when the other arm is connected with the lever.

14. In a cultivator, the combination with 50 cultivating devices, of a pair of movable plates or members, means for connecting the same with the cultivating devices, an operating lever provided with means for engaging either or both of the said plates or 55 members, and a shiftable locking device arranged to engage either of the said plates or members for holding the same when the other plate or member is connected with the operating lever.

60 15. In a cultivator, the combination with cultivating devices, of movable plates or members, means for connecting the same with the cultivating devices, an operating lever having a movable detent arranged to 65 engage either or both of the said plates or

members, and a locking device shiftable by the said detent and arranged to engage either of the said plates or members when the other is connected with the lever by the said detent.

70

16. In a cultivator, the combination with cultivating devices, of movable plates or members, means for connecting the plates or members means for connecting the plates or members with the cultivating device, an 75 operating lever located between the plates or members, a shiftable detent carried by the lever and provided with means for engaging either or both of the plates or members, and a shiftable locking device provided with engaging means located at the outer 80 face of the said plates or members, said locking device being operated by the detent and arranged to engage either of the said plates or members when the other is connected 85 with the lever by the said detent.

17. In a cultivator, the combination with cultivating devices, of movable plates or members, means for connecting the same with the cultivating devices, an operating lever, 90 a detent carried by the lever and arranged to engage either or both of the plates or members, operating mechanism mounted on the lever for actuating the detent and a shiftable locking device operated by the detent 95 and arranged to engage either of the said plates or members.

18. In a cultivator, the combination with cultivating devices, of movable plates or members, means for connecting the same 100 with the cultivating devices, an operating lever, a detent carried by the lever and arranged to engage either or both of the plates or members, operating mechanism mounted on the lever for actuating the detent, a 105 shiftable locking device operated by the detent and arranged to engage either of the said plates or members, and means for locking the operating lever in its adjustment.

19. In a cultivator, the combination with 110 cultivating devices, of movable plates or members, means for connecting the same with the cultivating devices, an operating lever, a detent carried by the operating lever and arranged to engage either or both 115 of the said plates or members, and operating mechanism for the detent mounted on the lever.

20. In a cultivator, the combination with 120 cultivating devices, of movable plates or members, means for connecting the same with the cultivating devices, an operating lever, a detent carried by the operating lever and arranged to engage either or both 125 of the said plates or members, and a shaft mounted on the operating lever and having a crank element connected with the detent for actuating the same.

21. In a cultivator, the combination with 130 cultivating devices, of movable plates or

members, means for connecting the same with the cultivating devices, an operating lever, a detent carried by the operating lever and arranged to engage either or both of the said plates or members, a shaft mounted on the lever and having a crank element connected with the detent, said shaft being provided with a handle or grip by which the lever is operated, and locking mechanism 10 for securing the lever in its adjustment, said locking mechanism having a latch lever arranged adjacent to the handle or grip of the shaft.

22. In a cultivator, the combination with 15 cultivating devices, of movable plates or members, means for connecting the same with the cultivating devices, a relatively fixed ratchet member, an operating lever provided with means for engaging the 20 ratchet member, a shiftable detent carried by the shiftable member and arranged to engage either or both of the said plates or members, and means operated by the detent for locking either of the plates or members 25 when the other is connected with the lever by the detent.

23. In a cultivator, the combination with cultivating devices, of movable plates or members having ratchet openings, means for 30 connecting the plates or members with the cultivating devices, an operating lever located between the plates or members, a shiftable detent provided with fingers arranged to engage ratchet openings of the 35 plates or members, and a shiftable locking device having projections or lugs arranged to engage other ratchet openings of the said plates or members.

24. In a cultivator, the combination with 40 cultivating devices, of movable plates or members having ratchet openings, means for connecting the plates or members with the cultivating devices, an operating lever located between the plates or members, a 45 shiftable detent provided with fingers arranged to engage ratchet openings of the plates or members, and a shiftable locking device having projections or lugs arranged to engage other ratchet openings of the said 50 plates or members, the fingers of the detent being of greater length than the lugs or projections of the locking device and the latter being moved into and out of engagement with the plates or members by the said 55 fingers.

25. In a cultivator, the combination with cultivating devices, of movable plates or members having separate sets of ratchet openings, means for connecting the cultivating 60 devices with the plates or members, an operating lever located between the latter, a shiftable detent carried by the lever and provided with projecting fingers arranged to engage one set of the ratchet

openings of each of the said plates or members, and a shiftable locking device having lugs or projections for engaging the other ratchet openings, said lugs or projections being located at the outer face of the plates or members and the said fingers being of a 70 sufficient length to extend through the plates or members for engaging the locking device to move the same into and out of engagement with the said plates or members. 65

26. In a cultivator, the combination with 75 cultivating devices, of plates or members provided with ratchet openings, an operating lever located between the plates or members, a detent carried by the lever and provided with means for engaging either or 80 both of the said plates or members, and a shiftable locking device operated by the detent and composed of two sides and a connecting portion, the sides being located at the outer face of the plates or members 85 and provided with means for engaging the same.

27. In a cultivator, the combination with cultivating devices, of plates or members provided with ratchet openings, an operating 90 lever located between the plates or members, a detent carried by the lever and provided with means for engaging either or both of the said plates or members, a shiftable locking device operated by the detent 95 and composed of two sides and a connecting portion, the sides being located at the outer face of the plates or members and provided with means for engaging the same, and having arcuate faces to receive the engaging 100 portions of the detent.

28. In a cultivator, the combination with cultivating devices, of movable plates or members, means for connecting the same with the cultivating devices, an operating 105 lever, a detent carried by the lever for engaging either or both of the plates or members, a shiftable locking device composed of two sides and a connecting portion, the sides being provided with means for 110 engaging the said plates or members, and a guide slidably receiving the connecting portion of the locking device.

29. In a cultivator, the combination with inner and outer cultivating devices, of 115 spaced supporting bars, a transverse shaft carried by the supporting bar, an arm fixed to the shaft and connected with one of the cultivating devices, movable plates or members mounted on the shaft, one of the 120 plates or members being provided with an arm connected with the other cultivating device, an operating lever mounted on the shaft, a detent carried by the lever for engaging the plates or members, and a 125 shiftable locking device actuated by the detent and provided with means for engaging the plates or members and slidably con-

nected with one of the supporting bars, whereby it is held against rotary movement on the shaft.

30. In a cultivator, the combination with 5 cultivating devices, of plates or members, means for connecting the same with the cultivating devices, an operating lever located between the plates or members and provided with spaced guides, a detent slidable in the 10 guides and provided with means for engaging the plates or members, and an operating shaft mounted on the lever and provided with a crank element located between the guides and connected with the detent.
- 15 31. In a cultivator, the combination with a frame, and pivotally mounted axles, of shiftable connecting means for the axles, shiftable cultivating devices, rack bars connected with the cultivating devices, a pinion 20 meshing with the rack bars, and an operating shaft for rotating the pinion, said operating shaft being also connected with the said shiftable connecting means and forming a lever for moving both the cultivating devices 25 and the shiftable connection laterally of the machine.
32. In a cultivator, the combination with a frame, and pivotally mounted axles, of a shiftable connection for the axles provided 30 with a loop, laterally movable cultivating devices, rack bars connected with the cultivating device, a pinion meshing with the rack bars, an operating shaft for the pinion, said operating shaft being arranged in the 35 said loop and forming a lever for moving the cultivating devices and the shiftable connection laterally of the machine, and means for locking the lever.
33. In a cultivator, the combination of 40 laterally movable cultivating devices, rack bars connected therewith, a guide having arms to receive the rack bars and supported solely by the same, a pinion also supported by the guide and meshing with the rack bars, 45 and means for rotating the pinion to move the rack bars simultaneously in opposite direction and for actuating the guide to move the rack bars simultaneously in either direction.
- 50 34. In a cultivator, the combination with shiftable cultivating devices, of rack bars connected therewith, a guide supported solely by and receiving the rack bars, plates mounted on the guide at the opposite faces 55 of the rack bars and provided with bearing openings, a pinion mounted in the bearing openings and meshing with the rack bars, and means for rotating the pinion to move the rack bars simultaneously in opposite

directions and for actuating the guide to 60 move the rack bars simultaneously in either direction.

35. In a cultivator, the combination with laterally movable cultivating devices, of rack bars connected therewith, a pinion meshing 65 with the rack bars and having a flared opening, said pinion being also provided with grooves, and a shaft provided with tapering ribs operating in the flared opening and engaging the grooves of the pinion. 70

36. In a cultivator, the combination of oscillatory hangers, cultivating devices carried by the same, supporting bars or members also mounted on the hangers, rack bars provided with arms connected with the supporting bars, a pinion meshing with the rack bars, and means for operating the pinion. 75

37. In a cultivator, the combination with a frame, pivotally mounted axles, and shiftable connecting means for the axles, of a 80 central crank element connected with the shiftable connection, transverse arms extending in opposite directions and operatively connected with the crank element, and treadles connected with the arms for 85 operating the crank element.

38. In a cultivator, the combination with a frame, pivotally mounted axles, and shiftable connecting means for the axles, of a central crank shaft having an arm connected 90 with the shiftable connection, said crank shaft being also provided with laterally extending arms, and treadles connected with the laterally extending arms for partially rotating the crank shaft. 95

39. In a cultivator, the combination of a frame having an axletree composed of spaced bars or members, a ratchet plate mounted between the bars or members and extending above and below the same, a bracket connected with the frame, pivotally mounted axles, a shiftable bar connected with the axles, a central shaft journaled in bearings of the bracket and the ratchet member and supported by the same, said shaft being 100 provided with a crank element connected with the shiftable bars, treadles, and means for operatively connecting the treadles with the crank shaft for partially rotating the latter. 110

In testimony, that I claim the foregoing as my own, I have hereto affixed my signature in the presence of two witnesses.

SILAS E. BAILOR
